CLAIM

The ornamental design for a handle for a shaving razor, as shown and described.

DESCRIPTION

FIG. 1 is a front perspective view of a design of a handle for a shaving razor of the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line razor cartridge illustrates the environment of the claimed design. The remaining broken lines illustrate portions of the handle for a shaving razor. None of the broken line disclosures form part of the claimed design. The dash-dot-dash broken lines define the bounds of the claimed and form no part thereof.
